ELECTROTYPE PRINTING ROLL FOR ADDRESSING MACHINES

Application filed May 9, 1930. Serial No. 451,019.

This invention relates to electrotype printing rolls that are especially designed for use in connection with addressing machines for printing the periodical bills issued by various public utilities at the same time the bills are addressed.

The electrotype roll with which the present invention is concerned comprises a cylinder or drum of which the entire circumferential extent is occupied by electrotype plates bearing printing characters that correspond with the makeup of the printed portion of the bill and which are not varied between issues unless a different design of bill is adopted. Thus the same electrotype plate is called upon to print an indefinitely large number of bills. Due to the extended use of the same electrotype plates, over and over again, and to the heavy printing pressure applied to the plates, it is found that in time the printing becomes uneven in intensity even though the type characters on the plates appear still to be sharp and usable. Investigation has indicated that this trouble is due to the fact that metal of the electrotype plates flows under the repeated pressures to which the plates are subjected so that the plates are caused to expand in area and thereby to buckle and lose their conformity to the surface of the drum to which they are attached. I have found after considerable experimenting and investigation that this trouble can be eliminated by making the electrotype plates of relatively small area and keeping them out of abutting engagement with each other and in so securing them to the supporting drum that the material of which the plates are composed can flow without changing the configuration of the plates or causing them to warp or buckle, and this constitutes the prime object of the present invention.

A further object of the invention is generally to improve the construction of electrotype printing rolls and plates for addressing machines.

Fig. 1 is a front elevation of a printing roll embodying the present invention.

Fig. 2 is a section taken along line 2—2 of Fig. 1.

Fig. 3 is an end elevation of the roll look-

ing at the right hand end of the roll of Fig. 1.

Fig. 4 is a view similar to Fig. 3 but viewing the roll from the left hand end of Fig. 1.

Fig. 5 is a sectional detail illustrating the manner of securing an electrotype plate to the roll taken along line 5—5 of Fig. 4.

Fig. 6 is a sectional detail taken along line 6—6 of Fig. 1.

Fig. 7 is a perspective detail of the peripheral portion of the roll and illustrating the grooves for holding the changeable date-printing characters.

Fig. 8 is a developed view of the printing roll and the electrotype plates thereon.

The printing roll here shown as embodying the invention includes a solid hub or disc 10 which is keyed to the driving shaft 12. The hub is provided with an outer peripheral face 14 on which is located the cylindrical drum 16 which bears the electrotype plates. The particular drum here shown is composed of three cylindrically shaped segments or sections 18, 20 and 22, see especially Fig. 4, which are located in end-abutting relation on the hub 10 and have grooves 24 in their inner faces in which the peripheral portion 14 of the hub is located and are secured to the hub by screws 26. The sections are provided with raised portions intermediate their side edges which cooperate to form in effect an endless raised flange or ledge 28 that extends completely about the periphery of the drum and preferably is corrugated or knurled to provide a driving face which engages the bill and advances it in non-slipping engagement with the electrotype plates carried by the roll as the roll is rotated.

The middle portion of the drum is also provided with an upstanding peripheral flange 30 in the middle thereof located beside the driving flange 28 in which the attaching screws 26 are countersunk and which provides a circumferentially continuous blank space that is free from printing characters and thus provides a space on the bill in which the address can be printed. The peripheral portion of the roll is provided with various electrotype plates *a*, *b*, *c*, *d*, *e* and *f*, see especially Fig. 8, and other plates *g*, *h* and *k*, which bear

certain type characters and particularly dates which are adapted to be changed each month prior to the printing and addressing of each new issue of bills. The electrotype plates, 5 however, are adapted to remain on the roll throughout the printing of an indefinite number of issues of bills.

The roll is provided with channels 32 which are peripherally endless and which have an axial width to accommodate the various electrotype plates. The opposite side edges 34 of the electrotype plates are dove-tailed or are tapered downwardly and outwardly from the top faces thereof as illustrated in Fig. 5 and the side walls of the plate holding channels are similarly shaped as at 36 to receive the plates and to hold them in engagement with the rolls. The outer peripheral edges of the plates at one end of the roll are engaged by the segmental rings 38, see especially Figs. 2 and 3, which are secured to the ends of the drum segments by screws 40 and which have axially directed flanges 42 that are located within and engage the inner faces of the drum segments. Said rings 38 upstand above the plate channels in the drum and have inwardly inclined inner faces 44 that engage the correspondingly shaped outer edges of the electrotype plates thereby to cooperate with the grooves 36 to hold the plates onto the drum. The plates at the other end of the drum are retained in place by segmental rings 46 which have inclined faces 48 that engage the inclined faces of the outer edge portions of the plates *d*, *e* and *f*. Said ring segments 46 have inwardly and downwardly tapered bottom walls 50 that are seated in a peripheral groove 52 formed in the drum and are secured to the drum segments by the screws 54. The drum segments are also provided with other dove-tailed channels 56 that receive the plates *g*, *h* and *k*, that bear the changeable printing data such as the dates. These plates are removable by sliding them lengthwise out of the channels. The confronting edges of the various electrotype plates are spaced apart by the spaces 58 which are sufficiently long in circumferential extent so that the plates can not engage each other when they become expanded in use and thereby buckle. While the plates are held firmly onto the periphery of the drum against any mechanical displacement thereon, the holding means is so arranged that the material of the plates can flow or the plates can grow in a circumferential direction without encountering any such obstruction as would cause the plates to warp or buckle. The axial widths of the plates are sufficiently small so that there is no appreciable growth or enlargement of the plates in an axial direction under the printing pressure. The plates also are sufficiently small in area so that they can expand freely without undergoing a deleterious

change in configuration. With this construction the plates have been found to have a much longer usable life than with the heretofore used construction wherein the electrotype plates were either peripherally continuous 70 or where held in abutting engagement or were so large in area that they would not maintain their configuration when subjected to continued use.

I claim:

1. A printing roll for addressing machines comprising a cylindrical hub, drum sections separately carried by said hub, cylindrically curved electrotype plates arranged on the drum sections, and occupying substantially 80 the entire circumferential extent of the drum, and plate securing means carried by the drum sections which engage the opposite side edges of said plates and secure them to the drum against displacement, there being spaces of 85 sufficiently long circumferential extent between the confronting ends of said plates so that the material of said plates can expand freely circumferentially without opposition and without abutting against each other in 90 said spaces whereby to maintain the original configuration of said plates and prevent warping thereof under extended use.

2. A printing roll for addressing machines comprising a cylindrical hub, drum sections 95 carried by said hub, a plurality of cylindrically curved electrotype plates located on the periphery of said drum sections and occupying collectively substantially the entire circumferential extent of the drum, there being vacant spaces of substantial circumferential extent between the confronting ends of said plates and at the ends of the sections, and plate securing means which frictionally engage the opposite edges of said plates and 100 retain them on said drum against displacement, the plates being capable of permanent expansion circumferentially while engaged by said frictional securing means into 105 said vacant spaces without abutting against each other whereby to preserve the original configuration of said plates and prevent the buckling thereof with extended use.

3. A printing roll for addressing machines comprising a circular drum composed of a 115 plurality of segments which collectively present a continuous cylindrical periphery, cylindrically shaped electrotype plates carried by said segments and occupying practically the entire circumferential extent of said drum and having their confronting ends separated by vacant spaces of substantial circumferential extent at the confronting ends thereof, and clamping means carried by said segments which frictionally engage the opposite side edges of said plates and retain them 120 against displacement.

4. A printing roll for addressing machines comprising a circular drum composed of a plurality of segments which collectively pre- 130

sent a continuous cylindrical periphery, cylindrically shaped electrotype plates carried by said segments and occupying practically the entire circumferential extent of said drum 5 and having their confronting ends separated by vacant spaces of substantial circumferential extent at the confronting ends thereof, said segments having means providing circumferentially extended dove-tailed channels in which said plates are located.

5. A printing roll for addressing machines comprising a circular drum composed of a plurality of segments which collectively present a continuous cylindrical periphery, cylindrically shaped electrotype plates carried 15 by said segments and occupying practically the entire circumferential extent of said drum and having their confronting ends separated by vacant spaces of substantial circumferential extent at the confronting ends thereof, 20 and clamping plates secured to said segments in frictional engagement with the side edges of said plates whereby to hold them against displacement from said segments, said clamping means permitting the material of said plates to flow circumferentially under the printing pressure and said plates being free 25 to enlarge circumferentially into said spaces without opposition.

30 In testimony whereof, I have signed my name to this specification.
